LUMINAIRE HOUSING

Donald E. Husby, Fairview Park, and Edmund L. Izzi,
Cleveland, Ohio, assignors to Westinghouse Electric
Corporation, East Pittsburgh, Pa., a corporation of
Pennsylvania

Application May 19, 1958, Serial No. 50,946

Term of patent 14 years

(Cl. D48—31)

Fig. 1.

Fig. 2.

Fig. 3.

Fig. 4.

Figure 1 is a top plan view of the luminaire housing, showing our new design;

Fig. 2 is a side elevation view of the luminaire housing;

Fig. 3 is a bottom plan view of the luminaire housing; and

Fig. 4 is an end elevational view thereof as seen from the right of Fig. 2.

The dominant features of the luminaire housing design are shown by solid lines.

We claim:

The ornamental design for a luminaire housing, substantially as shown and described.
